UNITED STATES PATENT OFFICE

130,001

DESIGN FOR A DOG COLLAR OR SIMILAR ARTICLE

Gilbert L. Morris, Cleveland, Ohio

Application February 3, 1939, Serial No. 82,770

Term of patent 3½ years

To all whom it may concern:

Be it known that I, Gilbert L. Morris, a citizen of the United States, residing at Cleveland, in the county of Cuyahoga and State of Ohio, have invented a new, original, and ornamental Design for a Dog Collar or Similar Article, of which the following is a specification, reference being had to the accompanying drawing, forming part thereof.

In the drawing,

Fig. 1 is a front elevation of a dog collar, showing my new design;

Fig. 2 is a rear elevation thereof;

Fig. 3 is a top plan view thereof; and

Fig. 4 is a view taken on line 4—4 of Fig. 3.

It is understood that the ornamentation in Figs. 1, 2 and 3 is continuous between the points shown in Fig. 3.

I claim:

The ornamental design for a dog collar or similar article, as shown and described.

GILBERT L. MORRIS.
